PETER R. WIMER, OF TRENTON, NEW JERSEY.

Letters Patent No. 102,901, dated May 10, 1870.

IMPROVEMENT IN CRUTCHES.

The Schedule referred to in these Letters Patent and making part of the same.

To all whom it may concern :

Be it known that I, PETER R. WIMER, of the city of Trenton, county of Mercer and State of New Jersey, have invented a Self-Adjusting Crutch; and I do hereby declare that the following is a full and exact description thereof, reference being had to the accompanying drawings and to the figures and letters of reference marked thereon.

The nature of my invention consists in the various motions given the arm-piece by means of the looseness with which the tubes are attached to the same, being secured with a nut inside of a brass plate, securely fastened to the cushion of the arm-piece, and being sufficiently loose to allow the arm-piece to play freely in every direction.

To enable others skilled in the art to make use of my invention, I will proceed to describe its construction and application.

Similar letters in the drawings represent similar parts of my invention.

Figure 1 represents a geometrical view of a crutch, showing my improvement therein.

Figure 2 represents a vertical section of one of the shafts of the crutch, showing the spiral spring F and the movable tube B at top, and the rod C extending

from the diaphragm G through the said spiral spring and movable tube, and which rod is attached in the plate E of the arm-piece by a movable nut.

Figure 3 represents a geometrical view of the rod C, and shows the nut e and manner it is fastened to the arm-piece.

Figure 4 represents a geometrical view of the movable tube B, which rests upon the spring F and supports the arm-piece.

Figure 5 represents the under plate of the arm-piece, which is secured to the cushion by three screws.

Figure 6 represents a section of said under plate E, showing the movable tube B and nut e, the rod C, and the mode of fastening the said under plate with the cushion.

What I claim as my invention, and desire to secure by Letters Patent, is—

The manner of fastening the rod C to the arm-piece by a nut, allowing a free motion thereof, substantially as set forth and claimed in the above specification.

PETER R. WIMER.
